COMBINED CLOTHESLINE, PULLEY, AND
CLOTHESPIN

Mario Esposito, Gloversville, N. Y.

Application November 15, 1950, Serial No. 195,759

7 Claims. (Cl. 211—119.02)

1

This invention relates to new and useful improvements in clothes lines of the type which are rigged to extend from a window to an outer support and have slidably fixed thereon a plurality of clothes clips.

Clothes lines of the type mentioned usually comprise a continuous loop mounted on suitable pulleys and having one leg thereof located below the other. Only the lower leg of the loop is utilized to support clothes.

One object of the invention is the provision of improved clothes clips slidably fixable on the lower leg of the said loop.

Another object of the invention is the provision of means associated with the window pulley for storing the said clips in a convenient position.

Still another object of the invention is to construct said means in such manner that the clips stored therein are prevented from riding out onto the upper leg of the line loop.

A still further object of the invention is to construct said clips and said means in such manner that the same are capable of being manufactured economically.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevational view of the means of the invention.

Fig. 2 is a plan view of said means.

Fig. 3 is a detached perspective view of the clothes clip of the invention.

Fig. 4 is a detached perspective view on a small scale of another portion of the means of the invention.

Fig. 5 is an enlarged sectional view on line 5—5 of Fig. 1.

Fig. 6 is an enlarged sectional view on line 6—6 of Fig. 1.

Fig. 7 is a side elevational view of a modified form of the invention.

Fig. 8 is an enlarged end view of the means of Fig. 7.

Fig. 9 is an enlarged sectional view on line 9—9 of Fig. 7.

Referring now to Figs. 1—6 wherein a first form of the invention is illustrated, the reference numeral 10 indicates a length of rope formed into a loop having one leg thereof located below the

2

other. One end of the loop is mounted on an ordinary clothes line pulley 11 which is secured by a yoke 12 to a suitable outer support such as a clothes pole. The other end of the loop is mounted on a pulley 13 to be more fully described hereinafter and which is secured by a yoke 14 which is usually secured to the side of a window.

According to the invention, a plurality of clothes clips 15 are slidably secured on the lower leg of loop 10 for the purpose of suspending articles of wash from the latter. Each clip 15 comprises a pair of sheet metal strap members 16 and 17. The latter having an upward extension 18 looped about the rope 10. The members 16 and 17 are spaced apart at their central portions and have ears 20 and 21 which support a pivot pin 22 interconnecting the members. A spring 23 is coiled about the pivot pin 22 and serves to maintain the inwardly offset lower portions of the members 16 and 17 together. At their lower ends the members 16 and 17 are provided with inturned flanges or teeth 24 which cooperate under the influence of spring 23 to grip between them an article of wash. The teeth 24 are spread apart to insert or remove an article of wash by pressing the upper end of member 16 against the member 17.

It will be seen therefore that the clips 15 are permanently mounted on the line 10 and are slideable along the latter to any desired position. Preferably the loops 18 are of such size as to have a slight frictional grip on the line adapted to prevent inadvertent sliding movements of the clips.

The pulley 13 which it will be remembered is secured to the side of a window by the yoke 14 comprises a pair of circular side plates 25 between which is secured in any suitable manner such as by welding, a pulley track 26. If desired the track 26 and the side plates 25 may be formed in one piece. The side plates 25 are of such diameter as to contain between them the entire length of a clothes clip 15 having its loop 18 engaged against the pulley track 26 as indicated in Fig. 1. As best shown in Fig. 5, the plates 25 are mounted on a pivot bolt 27 which also passes through the arms of yoke 14 and is provided with a nut 28. Suitable washers 30 and 31 separate the parts mounted on bolt 27 and assure free rotation of the plates 25. The arms of yoke 14 do not terminate at the pivot bolt 27 but project therebeyond at an upward inclination, ending a short distance beyond the periphery of the plates 25. The ends of yoke 14 serve to support an in-

verted sheet metal channel 32 whose upper edge is tangential to the periphery of the plates 25 and whose side walls are spaced apart the same distance as said plates 25. The one end of the channel 32 is formed arcuately to complement the peripheral curvature of the plates 25, but the other end of the channel is formed at right angles to the length thereof and is closed by ears 33 formed off the side walls of the channel. The ears 33 are provided with aligned holes 34 located on a line tangential with the pulley track 26. Thus the upper leg of rope 10 extends from said pulley track through said holes in a straight line.

The construction is such that as the lower leg of line 10 is reeled in to remove the articles of wash therefrom, the clips 15 travel around the pulley track 26 between the side plates 25 and into the inverted channel 32. The first clip 15 abuts the closed end of channel 32 and is prevented from riding out on to the upper leg of the line. Thus the said clips are conveniently stored within the said channel and the line need not be reeled back and forth to collect all of the clips. Further the said clips are protected from the elements within the channel.

The mounting of channel 32 on the ends of the arms of yoke 14 provides for the rocking of said channel about the pulley 13 as the position of the center portion of line 10 is varied by the weight of clothes hung thereon.

A modified form of the invention is illustrated in Figs. 7-9 wherein like parts are given the same reference numerals as hereinbefore with a prime added. In this form of the invention the side walls of channel 32' are provided each with a depending extension 35' whose one edge is a continuation of the arcuate end edge of the channel side wall. The other vertical edge of each extension 35' flares outward as it extends downward as best shown in Figs. 8 and 9.

The construction is such that the outwardly flared extensions 35' form a sort of funnel to guide angularly mispositioned clips 15' between the plates 25'.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A clothesline comprising a vertical loop of rope, a plurality of clothes clips slidably fixed on the lower leg of the loop, a pulley on which one end of said loop is mounted, a pulley track on which the other end of the loop is mounted, a pair of circular side plates secured to said track, each of a diameter such as to contain said clips within the periphery thereof, a pivot bolt on which said side plates are pivoted, a yoke also pivoted on said bolt and securing the pulley track and side plates to a window side or the like and an inverted channel secured to said yoke and aligned with said side plates, said channel having a closed end to limit the travel of said clips onto the upper leg of the loop.

2. A clothesline comprising a vertical loop of rope, a plurality of clothes clips slidably fixed on the lower leg of the loop, a pulley on which one end of said loop is mounted, a pulley track on which the other end of the loop is mounted, a

pair of circular side plates secured to said track, each having a diameter such as to contain the length of a said clip within the periphery thereof, a pivot on which said plates are journaled, a yoke having its side arms journaled on said pivot, an inverted channel secured to the ends of the yoke arms and having its top edge tangential with the peripheries of said side plates, and one end edge of each side wall abutting the periphery of a side plate throughout the length of the form or, ears closing the other end of the channel to limit the travel of the clips onto the top leg of the loop, and a hole in said ears through which said top leg extends.

15. 3. A clothesline comprising a vertical loop of rope, a plurality of clothes clips slidably fixed on the lower leg of the loop, a pulley on which one end of said loop is mounted, a pulley track on which the other end of the loop is mounted, a pair of circular side plates secured to said track, each having a diameter such as to contain the length of a said clip within the periphery thereof, a pivot on which said side plates are journaled, a yoke having its side arms journaled on said pivot, an inverted channel secured to the ends of the yoke arms and having its top edge tangential with the peripheries of said side plates, and one end edge of each side wall abutting the periphery of a side plate throughout the length of the form or, ears closing the other end of the channel to limit the travel of the clips onto the top leg of the loop, and a hole in said ears through which said top leg extends.

35. 4. In a clothes line comprising a vertical loop

of rope having one end mounted on a pulley, the combination, of a plurality of clothes clips slidably fixed on the lower leg of the loop, a pair of circular side plates, a pulley track fixed concentrically between said side plates, said side plates being of such diameter as to contain the length of a said clip completely within their peripheries, a pivot on which said side plates are journaled, a yoke having its side arms journaled on said pivot, an inverted channel secured on the ends of the yoke arms and into which the said clips are fed as they pass around the pulley track, ears closing one end of said channel and limiting the travel of said clips onto the upper leg of the loop, and a hole in said ears through which said upper leg extends.

5. In a clothes line comprising a vertical loop

of rope having one end mounted on a pulley, the combination, of a plurality of clothes clips slidably fixed on the lower leg of the loop, a pair of circular side plates, a pulley track fixed concentrically between said side plates, said side plates being of such diameter as to contain the length of a said clip completely within their peripheries, a pivot on which said side plates are journaled, a yoke having its side arms journaled on said pivot, an inverted channel secured on the ends of the yoke arms and into which the said clips are fed as they pass around the pulley track, the upper edge of the channel being tangential with the peripheries of said side plates, and the side walls of the channel being fitted to and aligned with the said side plates, ears closing one end of the channel and limiting the travel of said clips on to the upper leg of the loop, and a hole in said ears through which said upper leg extends, said hole being on a line tangential with said pulley track.

75. 6. In a clothes line comprising a vertical loop

of rope having one end mounted on a pulley, the combination, of a plurality of clothes clips slid-
ingly fixed on the lower leg of the loop, a pair of circular side plates, a pulley track fixed con-
centrically between said side plates, said side plates being of such diameter as to contain the
length of a said clip completely within their pe-
ripheries, a pivot on which said side plates are
journalled, a yoke having its side arms journalled
on said pivot, an inverted channel secured on the
ends of the yoke arms and into which the said
clips are fed as they pass around the pulley track,
ears closing one end of said channel and limit-
ing the travel of said clips onto the upper leg of
the loop, a hole in said ears through which said
upper leg extends, and a pair of depending ex-
tensions of said channel side walls, said exten-
sions being aligned with the said side plates on
one edge and flaring outward on the other edge
to guide clothes clips between said side plates. 20

7. In a clothes line comprising a vertical loop
of rope having one end mounted on a pulley, the
combination, of a plurality of clothes clips slid-
ingly fixed on the lower leg of the loop, a pair
of circular side plates, a pulley track fixed con-
centrically between said side plates, said side
plates being of such diameter as to contain the
length of said clip completely within their pe-
ripheries, a pivot on which said side plates are
journalled, a yoke having its side arms journalled
on said pivot, an inverted channel secured on the
ends of the yoke arms and into which the said
clips are fed as they pass around the pulley track,
ears closing one end of said channel and limit-
ing the travel of said clips onto the upper leg of
the loop, a hole in said ears through which said
upper leg extends, and a pair of depending ex-
tensions of said channel side walls, said exten-
sions being aligned with the said side plates on
one edge and flaring outward on the other edge
to guide clothes clips between said side plates. 25

ripheries, a pivot on which said side plates are
journalled, a yoke having its side arms journalled
on said pivot, an inverted channel secured on the
ends of the yoke arms and into which the said
clips are fed as they pass around the pulley track,
the upper edge of the channel being tan-
gential with the peripheries of said side plates,
and the side walls of the channel being fitted to
and aligned with the said side plates, ears clos-
ing one end of the channel and limiting the
travel of said clips onto the upper leg of the loop,
a hole in said ears through which said upper leg
extends, said hole being on a line tangential with
said pulley track, and a pair of depending ex-
tensions of said channel side walls, said exten-
sions being aligned with the said side plates on
one edge and flaring outward on the other edge
to guide clothes clips between said side plates. 15
